JEWELRY CLASP

Harry Radzinsky, New York, N. Y., assignor to
Katz & Ogush, Inc., New York, N. Y., a corpora-
tion of New York

Application September 14, 1939, Serial No. 294,821

7 Claims. (Cl. 24—241)

This invention relates to clasps or similar fastening devices such as are employed in necklaces, bracelets, wrist watches and other articles of jewelry.

5 The object of the present invention is to provide a clasp of this character which will be of substantial construction; which cannot be inadvertently opened; which will provide a smooth exterior without projecting parts and which can 10 be easily embodied in various designs to suit the requirements of the article of jewelry to which the clasp or fastening member is attached.

In the accompanying drawing, in which an illustrative embodiment of the invention is shown, 15 Fig. 1 is a top view of a clasp or fastening device made in accordance with the invention; Fig. 2 is a sectional view on the line 2—2 of Fig. 1, looking in the direction of the arrows; Fig. 3 is a top view of the clasp in open position; and Fig. 4 is 20 a view of the underside of the cover member or top of the clasp.

In the embodiment of the invention illustrated in the drawing, 1 indicates the elongated body member or base of the clasp. At one end, the 25 body member 1 is fixedly attached to a link 2 secured on the end of a bracelet, necklace, wrist watch band, or other article of jewelry, portions of which are shown at 3.

At its top, the body member 1 is formed with 30 a relatively shallow depression or recess 4 having end walls 5 near the opposite ends of the body portion. Extending downwardly from the bottom of the depression 4 is a slot 6 which extends transversely of the body member and which 35 is adapted for the removable reception of the cross-bar 7 of a link 8 secured on one end of the bracelet, necklace, wrist watch band or other article of jewelry 3.

At 9 is shown the cover member of the clasp, 40 the same conforming in general shape to the body member 1, the cover member having a top plate 10, which when the clasp is in closed position, overlies and covers the depression 4, so that the top of the clasp presents a smooth, un- 45 broken appearance, as seen in Fig. 1. Extending downwardly from the top plate 10 is a skirt or wall 11 which closely fits within the depression or recess 4, said skirt or wall forming a hollow chamber 12 in the body of the cover mem- 50 ber.

Secured within the chamber 12 of the cover member 9 is a spring 13, which is substantially C-shaped and the same is secured in place within the chamber by having its central portion soldered or otherwise attached to a portion of the

skirt or wall 11 at or about the point 14 in Fig. 4.

The spring 13 is provided with free ends 15 adjacent to each of which is formed an outwardly distorted portion 16 which projects through slot 17 (Fig. 2) in each of the end walls 18. The projecting portions 16 of the spring constitute resilient detents, which, when the cover member is in closed position, as in Figs. 1 and 2, snap into engagement with complementary recesses 19 provided in the opposite end walls 5 of the depression 4.

Cover member 9 is provided with a stem 20 which may be formed integral with the cover or may be an attached element, said stem constituting a pivot for the cover member and pivotally attaching the same at a central point to the base portion.

In its closed position, the clasp is shown in Figs. 1 and 2, wherein it will be seen that the plate portion 10 of the cover member overlies and covers recess or depression 4. At this time, the resilient detents 16, integrally formed as a part of spring 13, have snapped into engagement with recesses 19 in walls 5 and are thus holding the cover member against inadvertent rotative or turning movement with respect to the body member. At this time also, the cover member overlies and consequently closes, the open upper end of slot 6 so that movement of cross rod 7 out of said slot is prevented.

To open the clasp merely requires the application of sufficient manually-applied rotative force to the cover member 9 to cause the detents 16 to be forced out of the recesses 19 and the cover member swung around pivot 20 to the angular position of Fig. 3, wherein it will be noted that slot 6 is uncovered and the cross-bar 7 may be lifted out of the same to disengage link 8 from its engagement with said slot.

When the clasp is closed, it will be noted that the exterior of the same is smooth and unbroken and provides no projecting elements to catch onto clothing and thereby inadvertently open the clasp. The two detents at the opposite ends of the cover member serve to positively prevent rotative movement of the cover member when the device is closed. While two of these detents are shown, to provide a maximum of protection, one detent, located at one end only of the cover member might also be employed. This and other modifications may be made without departing from the spirit of the invention.

What I claim is:

1. A jewelry clasp comprising, a body member provided with a depression in one of its faces and

- 5 a slot extending across said depression, a wall at each end of the depression, a cover member rotatably attached to the body member and adapted to normally cover the slot therein, said cover member having a skirt extending into the depression, detents projecting out of said skirt, the end walls of the depression being provided with recesses for detachable engagement with said detents.
- 10 2. A jewelry clasp comprising, an elongated body member having a depressed upper face, a recessed end wall at each end of said depressed portion, a cover member pivoted on said body portion, said cover member having a hollow part fitting within the depressed portion, spring-pressed detents located at the opposite ends of said hollow part and projecting beyond said ends for snap engagement with the recesses in the end walls of the body member, the depressed portion of the body member being provided with an open-top slot which is closed by the cover member when the detents are in engagement with the recessed end walls.
- 15 3. A jewelry clasp comprising, a body member provided with a depression in one of its faces and a slot extending across said depression, a cover member pivotally attached to the body member and provided with a top portion conforming in shape thereto, said cover member being provided with a skirt portion fitting within the depression and conforming in shape thereto, spring means within the skirt having detent elements projecting out of and beyond the skirt, and recesses formed at the ends of the depression for snap engagement with said detent elements when said cover member is rotated to lie complementarily to the body member.
- 20 4. A jewelry clasp comprising, a body member provided with a depression in its top, a slot formed in said depression and extending downwardly therefrom for the reception of a cross bar on a jewelry link, a cover member pivoted to the body member and adapted to normally overlie and close the depression and slot, said cover member having a hollow chamber in which a C-shaped spring is located, said spring having free ends formed with detent portions extending out of the ends of the chamber, the depression hav-

ing end walls provided with recesses for detachable engagement with said detent portions.

5 5. A jewelry clasp comprising, a body member provided with an open-top slot in its upper face, a cover member provided with a stud by which it is pivotally attached to the body member, a spring within said cover member, said spring having end portions projecting out of the cover member and forming detents, the stud for pivotally attaching the cover member to the body member being located between the detents, the body member having end walls formed with recesses for detachable engagement with said detents to retain the cover member in closed position to cover the slot, said cover member being 10 rotatable to expose the slot when said detents are disengaged from the recesses.

15 6. A jewelry clasp comprising, a body member provided with an open-top slot extending to one face of the body member, a cover member rotatively attached to the body member and rotatable to open or close the slot, a spring within the cover member having detent portions projecting outside of the same, the cover member being rotatively attached to the body member at 20 a point between the detents and means on the body member for co-action with said detent portions to retain the cover member in closed position.

25 7. A jewelry clasp comprising, a body member provided with an open-top slot in its upper face, a cover member adapted to normally overlie the body member and cover and close the open top of said slot, said cover member having a hollow chamber defined by side walls and end walls, said cover member being pivotally attached to the body member at a central position between the end walls, a C-shaped spring contained within the chamber, said spring being secured at a point between its ends to one of the side walls and having free ends formed with detent portions extending out of the end walls of the chamber, said end walls having apertures through which said detent portions protrude, the body member having portions formed with recesses for detachable engagement with said detent portions.

30 HARRY RADZINSKY.
